UNITED STATES PATENT OFFICE.

EDGAR O. LOEBER, OF CLEVELAND, OHIO.

RECEPTACLE.

1,358,380.

Specification of Letters Patent. Patented Nov. 9, 1920.

Application filed December 19, 1919. Serial No. 345,993.

To all whom it may concern:

Be it known that I, EDGAR O. LOEBER, a citizen of the United States, residing at Cleveland, in the county of Cuyahoga and 5 State of Ohio, have invented certain new and useful Improvements in Receptacles, of which the following is a specification.

My invention relates to improvements in receptacles, and more particularly to safety 10 receptacle covers or lids, the primary object being to provide a generally improved safety or self-locking cover, the present embodiment being particularly designed and adapted for use in connection with what are 15 commonly known as "garbage cans," or the like, where it is desirable to provide a lid or cover which cannot be removed in the ordinary manner by the application of force upon the outer sides of the cover, such for 20 example as attempts to elevate or tilt the same by such animals as dogs, cats, or the like.

A further and very important object is the provision of an improved gravity handle 25 and latch adapted to be attached to one side of the lid or cover, the latter being provided with a rim having a downwardly and inwardly inclined latch housing to receive the depending latch portion of the handle latch, 30 said depending latch having its free end normally resting on the inwardly inclined portion of the housing and engaging the receptacle wall below and held in such position to engage the marginal projections or 35 outwardly extending rim of the receptacle can when the lid is raised independently of the latch, the gravity handle and latch being so pivoted relatively as to clear the projection or outwardly extending portion of the 40 receptacle when elevated initially and independently of the elevation of the lid or cover.

A further object is the provision of an improved safety receptacle lid or cover having 45 a depending rim provided with an inwardly struck projection opposite the gravity latch and adapted to be initially mounted on and engage one side of the marginal projection of the receptacle and to hold the lid 50 in position at such side so that the lid or cover is finally locked or unlocked through the medium of the handle latch at the opposite side of the lid.

With the above mentioned and other 55 ends in view, the invention consists in the novel construction, arrangement and com-

bination of parts, hereinafter described, illustrated in one of its embodiments in the accompanying drawings, and particularly pointed out in the claims.

Referring to the drawings, forming a part of this specification, Figure 1, is a side elevation, partly in central vertical section, of a container equipped with a cover and cover locking device, constructed in accordance with my invention, the parts being shown in locked position.

Fig. 2, a similar view of the same with the cover locking device in unlocked position preparatory to the removal of the cover 70 in the usual manner.

Fig. 3, a side elevation of the rear or receptacle engaging portion of the cover diametrically opposite the locking or latching portion thereof, and adapted to be initially 75 passed over the marginal projection or rim of the container to engage the same when the cover is in position.

Fig. 4, a top plan view of the same.

Similar numerals of reference designate 80 like parts throughout all the figures of the drawings.

The receptacle 1, may be of any suitable and convenient form, said receptacle, in the present instance, comprising the usual cylindrical receptacle or container body and provided at its upper marginal edges with an outwardly extending projection 1^a, said projection, in the present instance, comprising the usual outwardly extending beaded 85 rim.

The lid or cover 2, may likewise be of any suitable and convenient form and is provided with a depending rim 2^a, adapted to fit over the top of the receptacle or container and preferably provided at its lower edge with a beaded portion 2^b.

As a means of initially mounting and securing one side of the cover 2, to the upper marginal edges of the receptacle 1, one side 100 of the rim 2^a, is provided with a rim engaging portion consisting, in the present instance, of struck out tongues or projections 2^c. The rim engaging portions or members 2^c, are preferably struck inwardly (see Fig. 3) 105 forming downwardly and outwardly inclined portions and terminating in shoulders 2^d, to readily slip over the rim projection 1^a, and to engage on the under side of the same when the cover is down and retained by the gravity handle latch, herein-after referred to.

As a means of detachably securing the opposite side of the rim of the receptacle cover after the rim engaging portion 2^c, of the cover has been initially passed over the top 5 of the receptacle body, the diametrically opposite portion of the depending rim 2^a, is provided at its top with an opening 2^e, and a latch housing 2^f, said latch housing having a downwardly and inwardly extending 10 portion or wall 2^g.

As a means of so securing the lid or cover as to prevent the lid from being raised to an open position except through the initial raising or unlatching of the 15 locking device, the cover 2, is provided at one side with a gravity latch consisting of a handle portion 3, extending at one side of the cover and terminating in a depending latch 3^a, the latter extending downwardly into the housing 2^f, and having an 20 inwardly extending tip portion 3^b, adapted to normally rest against the receptacle wall below the rim projection 1^a, and to be held in such position by the co-operating action 25 of the downwardly inclined portion 2^g, of the latch housing. By reason of the construction described it will be apparent that when the lid or cover is raised without elevating the latch 3^a, through the handle 3, 30 the inclined portion 2^g, of the latch housing will maintain the free end of the latch in contact with the receptacle and cause the same to come into engagement with the rim projection 1^a, and thus prevent the removal 35 of the lid, and as a means of so pivoting the latch that the free end 3^b, will clear the rim projection 1^a, when elevated initially independently of the elevation of the lid, the inner end of the handle 3, is connected to 40 the top of the cover in such relative position that the free end of the latch will move upwardly in the arc of a circle and just within the top of the latch housing, such connection, in the present instance, consisting 45 of a hinge plate 4, secured by means of rivets 4^a, and provided with an upturned hinge loop 4^b, extending into an opening or slot 3^c, at the inner side of the handle 3.

It will thus be seen that the handle 3, of 50 the latch 3^a, forms a convenient means of detaching the cover 2, from the receptacle 1, as well as for handling the cover, as desired.

Having thus described one of the embodiments of my invention, without having set forth all the forms in which it may be made or all the modes of its use, what I claim and desire to secure by Letters Patent, is,—

1. In a receptacle, a receptacle having a 60 projecting rim, a cover having at one side a rim engaging portion and at the other a downwardly and inwardly inclined latch housing, and a gravity handle and latch pivoted on said cover, said latch having its 65 free end normally supported within said

housing to engage said projecting rim when the lid is elevated independently of said latch.

2. In a receptacle, a receptacle having a marginal projection, a lid provided with a 70 rim having an inwardly extending portion adapted to be initially mounted beneath and to engage one side of said receptacle marginal projection; said rim being provided with an opening and a downwardly and inwardly inclined latch housing, and a pivoted gravity handle above said lid terminating in a depending latch having its free end extending inwardly and normally resting on the inclined portion of said latch housing 75 and against the adjacent receptacle wall below said receptacle projection and adapted to engage the latter when the lid is raised independently of the latch, said latch being so pivoted as to be thrown outwardly to 80 clear the projection of the receptacle when elevated independently of the elevation of the lid.

3. In a receptacle, a receptacle body having an outwardly extending projection 90 about its upper marginal portion, a cover having a depending rim provided at one side with means for initially engaging one side of said projection of said receptacle, said rim being provided at its diametrically 95 opposite side with an opening and a wedge shaped latch housing, and a pivoted handle on said cover terminating in a depending latch member in said latch housing adapted to engage said receptacle projection and 100 be held in engagement therewith by said wedge shaped housing when the cover is raised independently of said handle.

4. In a receptacle, a receptacle body having an outwardly extending marginal projection, a cover having a rim provided on its inner side with means for initially engaging one side of said marginal projection, said rim being provided with a struck out latch housing having a downwardly 105 and inwardly inclined portion, and a pivoted gravity handle terminating in a depending latch member normally resting on said enclosed portion of said latch housing to engage 110 said receptacle projection when the cover is raised independently of said gravity handle, the latter being so pivoted relative to said receptacle projection and inclined portion of said housing as to clear said receptacle projection when elevated independently of the movement of said cover.

5. In a receptacle, a receptacle provided with a marginal projection, a receptacle lid provided with a depending rim having inwardly struck projections adapted to be initially mounted on and to engage one side of the marginal projection of said receptacle, said rim being provided at its diametrically opposite side with an opening at the top and a latch housing having a downwardly and 130

inwardly inclined portion; and a pivoted handle on said lid terminating in a depending latch operable in said housing, said depending latch having its free end normally resting on said inwardly inclined portion and engaging the adjacent receptacle wall below and adapted to engage the marginal projection of the receptacle when the lid is

raised independently of the latch, said latch being so pivoted relatively as to clear the ¹⁰ projection of the receptacle when elevated independently of the elevation of the lid.

In testimony whereof I have affixed my signature.

EDGAR O. LOEBER.
